UNITED STATES PATENT OFFICE.

EDWIN SAMUEL JOHNSON, OF NEW YORK, N. Y., ASSIGNOR TO STANDARD DREDGING COMPANY, OF NEW YORK, N. Y., A CORPORATION OF NEW JERSEY.

DISK CUTTER HEAD.

Application filed January 23, 1925. Serial No. 4,238.

The invention relates in general to a dirt cutters in their proper operative positions loosening or dredging machine of the hydraulic type, and specifically relates to a cutter head designed to be carried at the 5 outer end of the usual swinging ladder forming part of a dredging machine and which head is provided with cutting tools for the purpose of loosening the dirt, gravel and other material on the ground worked 10 upon, or on the bed of the body of water being dredged.

In similar devices now known it has been usual to mount different forms of blade and toothed drags or cutting tools at the end 15 of the ladder, in juxtaposition to the intake end of the suction tube used for withdrawing the loosened material. In all known forms of dredging machines the cutting tools carried by the head are operatively 20 connected with the cutting engine or other power plant to cause the tools to function. These devices have not proven economical in their action for much power is consumed, either in an idle movement of the tools or in 25 moving the material in such way that it was not drawn into the suction tube.

The present invention has for its primary object the providing of a simplified form of cutter head provided with cutting tools 30 which will feature economy both in their cost of construction, in their cost of replacement and in the cost of operation of the dredge equipped with the improved head.

One feature in which the invention contributes to this result is the providing of a 35 form of cutter head equipped with cutters which are operated solely as an incident of the sweeping lateral movement of the ladder and which cutters are actuated solely 40 from the usual ladder swinging engine. In this way the necessity for the use of actuating power is eliminated.

Another object of the invention and further featuring economy in operation is to 45 provide a cutting tool which will efficiently act on a limited amount of material and feed the same as a continuous stream into the path of the suction effect of the tube as the tool is moved by the ladder across the 50 path being dredged.

Still another object of the invention is to provide a cutter head which will function during the operative movement of the ladder in both of its directions of swing; which 55 will feature an automatic disposition of the

with each change of direction and in which a plurality of cutters may be carried on one head and each disposed to discharge its apportionment of the loosened material to a 60 single suction tube.

Various other objects and advantages of the invention will be in part obvious from an inspection of the accompanying drawings and in part will be more fully set forth 65 in the following particular description of two forms of mechanism embodying my invention, and the invention also consists in certain new and novel features of construction and combination of parts hereinafter 70 set forth and claimed.

In the accompanying drawings:—

Figure 1 is a view in side elevation, and with parts shown in vertical section, of a cutter head constituting a preferred embodiment of the invention; 75

Figure 2 is a plan view looking down upon the structure shown in Figure 1 with the cutters shown in an inoperative position in full lines and with the cutters shown in 80 an operative position in dot and dash lines.

Figure 3 is a view similar to Figure 1 showing a modified form of cutter mounting and control for the cutters; 85

Figure 4 is a plan view looking down upon the form shown in Figure 3 and with the rack and gear enclosing covers removed; and

Fig. 5 is a detail in axial section of the cutter mounting. 90

In the drawing and referring first to Figure 1 there is shown in dotted outlines the free swinging end of a ladder 10 carrying the suction intake tube 11 as is usual in dredging apparatus. It is further understood that the ladder and tube are swung by means of laterally extending flexible connections actuated by a swinging engine, not shown, and operatively connected to swing the ladder end in a substantially horizontal 95 plane back and forth as it is advanced along the channel being cut and that the ladder end is controlled in its vertical movement and positioned by flexible connections with a hoisting engine, not shown. 100

At the outer end of the ladder is positioned the heading particularly constituting the subject-matter of this disclosure. Referring to either of the forms herein illustrated there is shown a ladder end cast- 105

ing 12 provided with vertically spaced horizontal flanges 13 and 14 and a vertical, medial connecting web 15 coacting to form a rigid, mutually braced skeleton frame designed to be secured to the free end of the ladder. The upper plate flange 13 is provided with a pair of longitudinally extending transversely spaced apart triangular webs 16 and 17 between the upper ends of which is positioned a longitudinally extending link 18 secured in adjusted position to the ladder end casting by means of a bolt 19, passing through one of a line of apertures 20 formed in the adjacent end of the link 18.

Pivoted to the forward edge of the flange 13 is a cutter head 21 demountably hinged to the end casting by means of a long pivot bolt 22 arranged to provide relative angular movement between the head 21 and the casting 12 secured to the ladder. The head 21 comprises a wide webbed cutter plate 23 substantially rectangular in plan as shown in Figure 2 and provided centrally thereof with a pair of upstanding triangular webs 24 and 25. The forward end of the link 18 is pivotally secured between the webs 24 and 25 by a bolt 26. The adjustment provided by the shifting of the bolt 19 in the several apertures 20 permits of a vertical movement of the cutter head relative to the ladder and the bolt aperture connection thus provides a means for setting the head relative to the ladder in any desired adjusted angular position.

A T-shaped tiller 27 is pivotally mounted on an upstanding bolt 28 passed through a boss 29 constituting a vertical bearing formed on the plate 23 adjacent the center of its hinged rear edge. The tiller includes a forwardly projecting work arm 30 extending from opposite lateral sides of which are control cables 31 and 32 which, preferably, are independent of the ladder swinging means but are arranged to be operatively connected so that with each reversal of the direction of swing of the ladder there is a corresponding reversal of direction of the cutter disks hereinafter described.

Extending forwardly and longitudinally from each of a pair of laterally extending arms 33 and 34 of the tiller are disk actuating bars, which in the showing in Figures 1 and 2 constitute link rods 35 and 36 and which in the showing in Figures 3 and 4 constitute rack bars of which one bar 37 is shown in these figures. In either case the bars are designed to control two sets of disk cutters 38 of which three cutters are shown to each set in both forms herein illustrated with the sets disposed on opposite sides of the longitudinal medial line of the plate 23 beneath the same and on opposite sides of the intake end 39 of the suction tube 11. These cutters are each in the form of

a concaved circular disk formed of thin sheet metal with a sharp cutting edge 40. The cutting disk has a similarly shaped, but smaller, reinforcing rear plate 41 secured to the cutting disk by flush rivets 42. This rear plate is mounted for free rotary movement in a clamping frame 43 carried by a head 44 of a cutter arm 45. The cutter arm is mounted in a bearing 46 formed in the plate 23 for a limited rotary movement about a vertical axis indicated by the line $a-b$. The plane of the cutting edge of the disk indicated by the line $c-d$ in Figures 1 and 3 is inclined backward from its lower edge and in all positions faces the axis of swing of the ladder and is free to rotate about its axis indicated at $e-f$. In the showing the plane of the cutting edge is tilted backwardly at an angle of about 45° from the vertical, but this will vary under service conditions. The disks are controlled so as to face in the direction of swing of the ladder and for this purpose the arms 45 are controlled in their rotary movement about their vertical axis. In the showing in Figures 1 and 2 the arms 45 are each bent to overlap the upper edge of their respective disks so as to dispose each disk with its axis of rotation $e-f$ intersecting the axis of swing $a-b$ of the arm and thus tend to minimize drag on the disks as they are rotated about their vertical axis.

In the showing in Figures 3 and 4 the arms 45 are J-shaped with the disk cutters disposed each in advance of the axis $a-b$ of their associated mounting arms. For the purpose of swinging the disk cutters to face in the direction of swing of the ladder, the arms 45 of each set are connected, in the form shown in Figures 1 and 2, by means of links 47 with the shift rods 35 and 36 respectively, and in the showing in Figures 3 and 4 the arms are similarly connected by a rack and pinion connection, the rack 48 being formed on the rod 37 and engaging with gear 49 secured to the arm 45. The rack and gear connection is housed in a casting 50 positioned on top of the plate 23 in the form shown in Figure 3.

Stops 51 and 52 are provided on the plate 23 to limit the movement of the arms 33 and 34 and thus locate the angular position of the disks as they are rotated into their operative position.

It is within the scope of this disclosure to assume that the cables 31 and 32 can be utilized as the means for swinging the ladder in its reciprocating movement. In this case a pull on one of the cables, such as the cable 32, will act first to shift the cutters and then act through the stop 51 to shift the head as a whole.

In operation it will be understood that as the ladder is moved from its normal centered position as shown in full lines in the

several figures to one side or the other, such for instance, as a swing anticlockwise, the pull on the cable 32 in Figure 2 will cause the disk cutters to shift from their normal 5 forwardly facing positions shown in full lines into a laterally facing shifted position as shown in dotted lines in Figures 2 and 4. The engagement of the arm 33 with the stop limits the rotating of the disks 10 and in the disclosure the turn is shown to be approximately 45°. When so shifted the ladder is swung in the direction in which the disks are facing and the cutting operation is continued to the end of the lateral 15 ladder swing. As the cutters are forced angularly through the soft material at the bottom of the river bed the reaction of the material on the disks will cause the same to rotate each about its own axis $e-f$ in this 20 instance in an anticlockwise direction with the result that they tend to cut their way through the material and endeavor incidentally to bury themselves in the material. Any lowering movement of the head as a 25 whole is resisted by the cables which hold the ladder and therefore the disks not being able to lower themselves will react on the material to elevate and lift the same. As the cutters move along the ground each 30 cutter sinks or is drawn down into the soft material to form a kerf and all the cutters coact to form six closely positioned parallel kerfs in the case of the illustrated machine. This means that each cutter has but a limited 35 amount of material to work up but in the aggregate the six cutters can loosen a relatively large amount of material.

The saucer-like, concaved work face of each cutter acts as a scoop to lift the cut 40 portion of the material away from the bed. As this action takes place at the intake end of the suction tube the loose material will be withdrawn from its position adjacent the disks in accordance with the usual practice.

When the desired width of channel has been cut the movement of the ladder is 45 intercepted; tension is placed on the other cable 31 to turn the disk cutters until they face in the opposite direction and the ladder is then swung in said opposite direction. During this reverse swing of the ladder the disk cutters again act on the material to loosen the same and the operation 50 is continued, the ladder swinging back and forth on its reciprocatory movement as the dredge is slowly advanced along the channel being dredged.

By means of a device of this character it 55 is possible to dispense with all disk cutting operating mechanisms, such as the usual cutting engine, and to utilize the power plant which is at present employed solely to swing the ladder. There is featured a cutting action 60 of the disks in distinction from the

usual blade or tooth drag and the providing of an easier loosening of the material than is possible with known forms of dredging tools.

The construction of the castings feature 70 integrally formed reinforcements which tend not only to provide a mutually braced structure but also provide rigid bearings for the cutter arms for the tiller and other parts of the cutter control.

Having thus described my invention, I claim:

1. In a dredging machine, the combination of a ladder mounted for reciprocatory movement horizontally, a cutter head carried thereby, two sets of rotary cutters carried by the head, one set on each longitudinal side of the ladder, a suction tube having its intake end positioned between the sets of cutters and each cutter mounted for a limited turning movement about an upright axis and free to turn about an axis perpendicular to the plane of its face, means connecting the cutters of each set for simultaneously turning the same about their respective upright axes, means for swinging the ladder in its reciprocatory movement and means controlled by the change of direction of said ladder swing and connected to the last named means for simultaneously shifting the positions of both sets of cutters.

2. In a dredging machine, the combination of a ladder pivotally mounted at one end for reciprocatory horizontal swinging movement, a cutter head at the free end of the ladder, a set of disk cutters carried by the head and connected to face in the same direction, means connected to the cutters for shifting them to face in the direction of movement of the swinging head as it moves back and forth with the reciprocatory ladder and a suction tube having its intake end adjacent the cutters.

3. In a dredging machine, the combination of a two part ladder heading and with the parts hingedly connected, one of said parts adapted to be secured to a ladder of a dredging machine and the other part provided with a set of disk cutters each pivoted to said other part to rotate about their respective axes and means for securing the parts in adjusted angular relation thereby to locate the axes of the disk cutters relative to the ladder.

4. In a dredging machine, the combination of a support a web projecting vertically therefrom, a cutter head hinged to the support for relative movement about a horizontal axis and provided with a web and means extending across the axis and connecting said webs for securing the head relative to the support.

5. In a dredging machine, the combination of a support including a plate provided

- 4
- with an upstanding web, a head including a plate provided with an upstanding web, a hinge connection between the plates and an adjustable link connection between the webs.
- 5 6. In a dredging machine, the combination of a cutter plate webbed to provide integral reinforcements for the plate, certain of said reinforcements constituting bearings extending through the plate and cutter mechanism including a shaft mounted in said bearings.
- 10 7. In a dredging machine, the combination of a cutter plate provided with integral reinforcements, certain of said reinforcements constituting cylindrical bearings, and cutter mechanism carried by said plate and including shafts journalled in said bearings.
- 15 8. In a machine for dredging a channel, the combination of a support mounted to be swung bodily in a horizontal plane transversely of the length of the channel, a pair of cutters depending from the support and positioned on opposite lateral sides thereof and means operatively connected to the support for swinging the support horizontally and thus cause the cutters to function as they are swung across the channel.
- 20 9. In a dredging machine, the combination of a cutter plate, two sets of cutters carried by said plate, depending therefrom and disposed on opposite sides of a longitudinal medial plane and a suction tube positioned in said medial plane and having its intake end in juxtaposition to the cutters of each set.
- 25 10. In a dredging machine, the combination of a swinging ladder, a cutter head at the free end of the ladder, a plurality of disk cutters, each mounted on the head, free for rotary movement about its own axis and independent of each other, said cutters each mounted for swinging its axis to cause the disks to face the axis of swing of the ladder and means for swinging the cutters to cause the same to face in the direction of movement of the swinging ladder.
- 30 11. In a dredging machine, the combination of a support mounted to be reciprocated bodily in a horizontal direction, two sets of cutters carried by the support, each of said cutters mounted on the support for rotary movement about a vertically disposed axis, a single control operatively connected to all of the cutters for swinging the same over a limited angle about their respective vertical axis and causing the cutters to face in the direction of movement of the support and means for mounting each of said cutters to permit free rotary movement of each cutter about an axis intersecting the vertical axis of its engagement with the support.
- 35 12. In a dredging machine, the combination of a support mounted to be reciprocated bodily in a horizontal direction, two sets of cutters carried by the support, each of said
- cutters mounted on the support for rotary movement about a vertically disposed axis, and a single control operatively connected to all of the cutters for swinging the same over a limited angle about their respective vertical axis and cause the cutters to face in the direction of movement of the support.
- 40 13. In a dredging machine, the combination of a support, two sets of cutter arms journalled in said support, a pair of connecting bars, one for each set of arms for shifting the arms of each set in unison, a single control for both bars, and a tiller having laterally extending arms connected respectively to said bars, and means engaging the tiller to cause all of the arms to shift simultaneously.
- 45 14. In a dredging machine, the combination of a support, two sets of cutter arms journalled in said support, a pair of connecting bars, one for each set of arms for shifting the arms of each set in unison and a single control for both bars.
- 50 15. In a dredging machine, the combination of a support, a cutter arm journalled in the support for movement about a vertical axis, a circular cutter journalled on said arm and having its outlining edge disposed in a plane inclined to said vertical axis, and means for moving the support and for turning said arm thereby to shift the position of the cutter relative to the support.
- 55 16. In a dredging machine, the combination of a support mounted to be swung back and forth horizontally, a cutter arm journalled in said support, a disk cutter carried by said arm and rotated by the horizontal swing of said support, a tiller carried by the swinging support and connecting means between the tiller and arm for turning the cutter automatically to face in the direction of movement of the support.
- 60 17. In a dredging machine, the combination of a support, an arm journalled in said support for movement about a substantially vertical axis and normally fixed relative to the support while in dredging position, and a circular cutter disk carried by the arm and mounted for free rotary movement about its axis, the axis of the circular cutter being at an angle to the vertical axis of said arm and fixed relative to the support when in operative dredging position.
- 65 18. In a dredging machine, the combination of a ladder mounted to be swung back and forth horizontally, a support pivotally connected to the free end of the ladder, an arm journalled in said support for movement about a substantially vertical axis, an angularly disposed circular cutter disk carried by the arm and mounted for free rotary movement about its axis, means engaging the arm for swinging the plane of the cutting edge to face in the direction of move-

ment of the support and means for moving the support and for causing the disk to rotate.

19. In a dredging machine, the combination of a support, an arm journalled in said support for movement about a substantially vertical axis, a circular cutter disk carried by the arm and mounted for free rotary movement about its axis, said circular cutter disk having a cutting edge disposed in a plane perpendicular to its axis of rotation and inclined to the vertically disposed journaling axis of the arm.
20. In a dredging machine, the combination of a disk shaped cutter free to rotate about its axis, said cutter having a cutting edge disposed in a plane inclined from the vertical and means for reciprocating the cutter back and forth along a horizontally disposed path extending at an angle to said plane.

21. A dredge cutter comprising a set of disk-shaped cutters with their cutting edges disposed in parallel planes, each cutter free to rotate about its axis, and said axes being parallel to each other and relatively offset from each other.

22. In a dredging machine, the combination of a cutter disk having a continuous concaved face outlined by a circular cutting edge and means for mounting the disk for free rotary movement about its axis and said disk receiving its rotary impulses at its periphery and otherwise free of driving mechanism.

23. In a dredging machine, the combination of a support mounted for reciprocatory linear movement and a circular concaved cutter disk having a curved face continuous from edge to edge across its axis mounted on the support for free rotary movement about its axis and inclined to the path of movement of the support.

24. In a dredging machine, the combination of a tool support mounted for bodily horizontal movement across the ground to be loosened, a tool carried thereby having a

cutting edge movable relative thereto and having a concaved side free of projections facing in the direction of movement of the support, said tool being free of any actuating power and the cutting edge deriving its cutting movement solely from its reaction with the ground as it is moved with its support across the ground and in the direction in which the concaved side is facing.

25. In a dredging machine, the combination of a rotary disk cutter, means for moving the same along a substantially straight path, a suction tube having its intake end disposed adjacent said cutter and movable therewith and means confined to one side of the disk cutter for mounting the cutter with its axis of rotation disposed at an angle to the length of said path and said cutter having its opposite side free of projections and continuous between opposite edges.

26. In a dredging machine, the combination of a tool, means for moving the same bodily along a path to be dredged, said tool including a disk cutter mounted for free rotary movement with its circular edge disposed in a plane extending approximately 45° to the vertical, and operatively disposed to be rotated by the engagement of the lower side of said edge with the ground as the cutter is moved along the same with the tool.

27. In a dredging machine, the combination of a cutter head mounted for reciprocatory movement transversely of a path to be dredged, a disk cutter mounted on the head for free rotary movement, means for shifting the disk cutter to face in the direction of movement of the head, the face of said cutter being inclined to face upwardly and the circular edge outlining said face being operatively disposed to derive its power to rotate from its engagement with the ground as the head is moved on its reciprocatory movement.

Signed at New York city in the county of New York and State of New York this 22nd day of January A. D. 1925.

EDWIN SAMUEL JOHNSON.
